Application November 2, 1934, Serial No. 751,165

19 Claims. (Cl. 88—24)

This invention relates to photography, and more particularly to a machine by which prints can be rapidly made.

One object of my invention is to provide a machine of the class described in which projection or enlarged prints can be made from a relatively small negative. Another object of my invention is to provide a printing machine in which negatives can be used in strip form and in which a means is provided for rapidly locating the negative with respect to the printing paper. Another object of my invention is to provide a machine in which the printing paper need only be handled once during the printing operation. Another object of my invention is to provide a printing machine in which the platen automatically moves printing paper from its printing position. Another object of my invention is to provide a printing machine in which means is provided for masking the prints by moving the negative. Another object of my invention is to provide a machine in which negatives in strip form may be held flat and may be readily adjusted for printing. Still another object of my invention is to provide a machine in which the printing light can be quickly operated, and other objects will appear from the following specification, the novel features being particularly pointed out in the claims at the end thereof.

Coming now to the drawings wherein like reference characters denote like parts throughout:

Fig. 1 is a front plan view of a printing machine constructed in accordance with a preferred embodiment of my invention.

Fig. 2 is a section taken on line 2—2 of Fig. 1 showing in elevation the top of the printing machine table.

Fig. 3 is an enlarged fragmentary sectional view through the negative holding and adjusting mechanism, being taken on line 3—3 of Fig. 2.

Fig. 4 is a section through the printing machine shown in Fig. 1 taken on line 4—4 of Fig. 1.

Fig. 5 is a section through the illuminating system and lamphouse, being taken on line 5—5 of Fig. 1.

Fig. 6 is an enlarged top plan view of the upper part of the printing machine showing the printing panel, platen, and platen operating mechanism.

Fig. 7 is an enlarged fragmentary sectional view through a portion of the machine shown in Fig. 1, showing the lamp control and the shutter used in conjunction with the lamp control.

Fig. 8 is a fragmentary sectional view showing

the switch operating mechanism in a different position from that shown in Fig. 7.

Fig. 9 is a fragmentary enlarged sectional view showing the platen in a raised position and the focusing plate in a focusing position.

Fig. 10 is a view similar to Fig. 9, but with the parts in a reversed position.

This invention comprises broadly a machine especially designed to take care of making enlarged prints from relatively small negatives, the negatives being held flat in strip form by a special type of negative holder. This negative holder can be moved rapidly through a light beam so that an image carried by a negative can be projected upon a focusing plate which enables an operator to view the image and properly position it with respect to the printing panel. Thus, the machine resembles both a printing and an enlarging machine.

Referring to Fig. 1, wherein a preferred embodiment of my invention is shown, the printer may be conveniently built into the form of a table having a top 1 supported by a plurality of legs 2 which may be braced together, as indicated at 3. The table top 1, as best shown in Fig. 2, preferably carries a support 4 which may have a base and which may have upstanding flanges 5. These members carry an upper table top 6 which supports a plate 7 having a cut-out opening 8, which will be referred to as the printing panel and which is to define the size of the prints to be made.

Referring particularly to Fig. 6, the printing panel 8 is a large opening formed in the plate 7, there being spaced from the large opening a series of smaller openings 9. The purpose of these openings is to permit hinged paper engaging hooks 10 to pass through the openings when the platen is lowered to hold the paper flat for exposure. This is best illustrated in Figs. 9 and 10.

In Fig. 9 the platen 11, which is shown in an inoperative or raised position, is carried by the parallel arms 12 pivoted at 13 and 13' to the upper table top 6. These arms are extended at 14 to support on the pivots 15 the focusing or locating plate 16, which will be more fully described hereinafter. With this construction it is obvious that the platen and the focusing plate will be moved together in parallel relation and in opposite directions with respect to the printing panel 8.

The platen 11 is provided with four brackets 17 to which the hooks 10 are pivoted at 18, these hooks being encircled by springs 19, as shown in Fig. 6, tending to hold the hooks with the ends 55

lying beneath the pad 20 on the bottom of the platen 11 which is adapted to press a sheet of paper flat for exposure.

As also shown in Fig. 9, two of the hooks 10 pivoted to the rear edge of the platen 11 are provided with elongated arms 21 adapted to contact with the stops 22 carried by the bracket 23. Thus, when the platen is moved to its inoperative position, shown in Fig. 9, the two rear hooks 10 will be swung in the direction shown by the arrow against the pressure of the springs 19 to release the rear edge of a sheet of paper P so that the paper will drop, and by hitting the inclined slide 24 will pass downwardly between the side flanges 25 of a chute 26, best shown in Fig. 1. This chute leads either to a developing tray or to a container for the exposed sheets of paper.

When the platen is moved from its inoperative position, shown in Fig. 9, to its operative position, shown in Fig. 10, the hooks 10 pass through the small openings 9 in the plate 7, snapping onto a sheet of paper P which may be laid over the opening 8. After an exposure has been made and the platen returns to its Fig. 9 position, the four hooks carry with them the sheet of paper suspended beneath the platen until the rear hooks are released by arms 21 striking the stops 22.

In small negatives, if the exposures should be cut apart, the films are difficult to handle and to properly position for printing. Consequently, I provide a negative holding carriage, best shown in Figs. 2 and 3, which will take the entire strip of negatives without cutting them apart. As indicated in Fig. 3, the negative holder may consist of an elongated frame 27 in which two glass plates 28 and 29 are mounted. Plate 28 is fixedly mounted in the frame 27 and plate 29 is carried by a pair of hinge elements 30 which are pivoted at 31 to the elongated frame 27. Plate 29 may be held in a closed position by means of a latch 32. A strip of negatives F is laid between the plates 28 and 29 so that the individual exposures are all held flat.

The elongated frame 27 is provided with a series of rollers 33 mounted on shafts 34 so that the carriage can run freely back and forth over the table top 1. The carriage has serrated side edges 35, as indicated in Fig. 1, so that it can be readily moved and controlled by an operator. The path of movement of the carriage 27 is defined by a guide rail 36. Referring to Fig. 2, this guide rail is provided with an aperture 37 adapted to engage either pin 38 or pin 39 carried by the table top. At the opposite end of the guide rail 36 the rail is guided by a cam 40 or by a cam 41 also carried by the table top, these cams being mounted on a post which can be turned or rotated by means of a handle 42.

When the negative holder is positioned as shown in Fig. 2, the operator merely presses in upon the knurled edge 35 to roll the carrier or its rollers 33 across the table top to guide the various negative areas across the light beam which is defined by the opening 43 which is formed in a circular plate 44 in the table top 1. If the operator should find that the negatives are not properly positioned, the angle of the negative holder relative to the light beam can be adjusted by turning a knurled head 42 so that a cam, such as 40, may contact with the rail 36 and cause the rail to turn about its pivot 38, thus varying the frame line. With the holder as positioned in Fig. 2, the negatives should have the exposure areas run longitudinally of the film. However, if the greatest length of the individual exposures run cross-wise of the

film, the rail 36 should be removed from the position shown in Fig. 2 and the aperture 37 should be placed over the pin 39 so that the rail will run substantially at right angles to its position in this figure. If the rail is so changed, the end of the rail will rest on the cam 41, but in either case the negative holder can be positioned by turning the knurled knobs 42.

In order to determine the position of the negative with respect to the printing panel 8, the focusing plate is used. When the platen is raised, as shown in Fig. 9, the focusing plate 16 lies over the printing area. This plate is preferably painted or coated with a white or bluish-white coating which will reflect an image formed upon it by means of the objective 45, as shown in Fig. 4. This image can be viewed by an operator by looking at the mirror 46, which is arranged at a slight angle to the focusing plate to facilitate viewing. Thus, if the operator sees that the image is not properly centered by this reflected image, he can manually adjust the negative carrier to properly frame the picture. Usually, it will be only necessary to adjust the position of rail 36 once to frame all of the picture areas carried by the film holder 27. This operation can be accomplished very quickly, and after the film has been once properly framed, successive exposures can be made rapidly by causing the negative holder to move one frame at a time as the carriage 30 rolls across the table top, guided by the rail 36.

The light beam, through which the negative holder passes, is provided by the optical system shown in Fig. 5, wherein a lamp 48 is carried in a socket 49, there being an enclosure 50 with a suitable opening 51 to permit air to enter and to pass up around the lamp in the direction shown by the arrows up through the chimney 52 which extends up through the table top 1, past the upper table top 6, as is indicated in Fig. 1.

Behind the lamp 48 there is a reflector 53 and in front of the lamp, a pair of condenser lenses 54. If desired, a ground or opal glass, or other light diffusing medium 55 may be inserted in the slideway 56 provided in the lamphouse, designated broadly as 57. A mirror 58 is mounted on a spring carriage 59, one end of which engages a pin 60 and the other end of which may be adjusted by a screw 61. This is purely a factory adjustment and after once being set, need not be further altered.

Above the mirror 58 is a second set of condenser lenses 62 which project a beam of light through the masking opening 43 in the circular plate 44.

The lamphousing 57 as a whole can be readily removed by releasing the wing nuts 63 and 64 which pass through slots 65 and 66 in the upper wall 67 of the lamphouse. I have found it convenient to mount on a bracket 68 a paper box 69 having a removable top 70, since this brings the paper close to the printing panel 8. In order to position this paper, I provide a series of paper guides, some fixed and others movable, as will now be described.

Referring to Fig. 6, the plate 1 carries to each side of the printing panel 8 a pair of guiding plates 71, the bottom edges of which 72 are spaced from the opening 8 evenly to position the sides of a sheet of paper thereon. The front edge of a sheet may be positioned by a guide 73, and while I have shown the guides 71 and 73 fixedly mounted on the plate 7, these can be readily made adjustable if it should be desirable to do so.

The plates 71 and 73 constitute the fixed guides and the movable guides consist of a pair of arms 75

74 which extend upwardly through the small apertures 9 from the focusing plate. These arms are best shown in Fig. 9 wherein they extend up parallel to the plate 73 and spaced from this plate. 5 With the parts in the position shown in Fig. 9, an operator removes a sheet of paper from the box 70, merely dropping it between the guides 71, 71, 73, and 74. The platen 11 is then lowered, and as the bell-crank levers 12 and 14 swing about 10 their pivots 13 and 15, the movable arms 74 move downwardly out of the apertures 9, leaving the paper properly positioned on the printing panel and giving room for the platen pressing surface 20 to press the paper P flat over the printing 15 panel. Thus, the focusing plate not only assists an operator in properly adjusting the negative to a printing position, but at the same time carries one of the sets of paper guides.

The platen operating mechanism will next be 20 described. The platen 11, as above explained, is pivotally attached to the arms 12 of bell-crank levers, having opposite arms 14 carrying the focusing panel 16. The shaft 13, to which one set 25 of bell-crank levers 12 and 14 are attached, extends through a suitable bearing 75 into an L-shaped opening 76 in the upper table top 6, as best shown in Fig. 6. There is a crank 77 carried by the shaft 13 and this crank carries a stud 78 on which a link 79 is pivoted at the rear end, 30 this link being pivoted at 80 to a handle 81 which is attached at 82 to a pivot carried by the support 83. As best shown in Figs. 6 and 8, when the handle is moved in the direction shown by the arrow, about its pivot 82, the link 79 and the crank 77 will be turned and the platen will be 35 moved from the position shown in Fig. 9 to that shown in Fig. 10. A spring 84 tends to return the platen to its inoperative position as soon as the handle 81 is released, although the tension 40 on this spring is adjusted so that very little pressure is required upon the handle 81 to cause the platen to function.

The handle 81 is arranged so that a surface 85 of the handle lies in the path of a knob 86, as 45 best shown in Figs. 7 and 8. The handle 81 is moved until the platen is completely lowered, in which position the handle will be approaching the knob 86. Further movement of the handle causes this knob to be depressed so that the rod 50 87 which passes through an aperture 88 in a support 89 will rock the lever 90 upon its shaft 91. Shaft 91 also carries a shutter 92 so that when the rod 87 is moved in the direction shown 55 by the arrow in Fig. 7, the shutter 92 quickly swings up out of the path of the light beam which passes through the objective 45. The timing of the movement of these parts is such that the lamp is turned on as the platen reaches the printing panel and the shutter is opened slightly after this time. Consequently, when the handle 81 is raised, the shutter 92 swings across the light beam and the lamp 48 is turned off in the order named.

The switch for the lamp is shown in Fig. 7 as 60 being a mercury switch 93 carried by a support 94 pivoted at 95 and having a curved end 96. This end is adapted to be engaged by a cam 97 carried by the shaft 13. The curvature of the part 65 96 is such that the first part of movement of cam 97 quickly tilts the mercury switch 93 from its open position in Fig. 7 to its closed position in Fig. 8, in which position contact is made through wires 98 and 99. Further movement of the cam 70 97 merely causes this part to ride idly over the

curved surface 96 holding the switch in its closed position. Thus, the light beam can only pass through the objective 45 when the platen is pressing the paper flat for exposure. The shutter 92 permits the light beam to pass through the objective, and since the lamp is turned on before the shutter operates, it can reach its full brilliance before the exposure is started. 5

There is a second way of operating the shutter 92 which is necessary because in order to position the negative, the lamp 48 must be turned on 10 and the shutter 92 must pass the light beam through the objective 45. This is accomplished in the following manner. Referring to Fig. 4, there is a push-button 100 on the end of a rod 101, this rod impinging upon a lug 102, best 15 shown in Fig. 7. Thus, when the push-button is pressed in the direction shown by the arrow, the shaft 91 is rocked, this manually rocking the shutter 92. 20

As the lever 90 turns on its pivot 91, a rod 103 will be moved upwardly or in the direction shown by the arrow in Fig. 7, and since this rod is pivoted at 104 to the switch carrier 94, the switch is turned to the position shown in Fig. 8. This 25 movement, of course, does not affect the location of the platen, since it is entirely independent of it. It is merely used for momentarily permitting a beam of light to pass through the objective 45 for positioning a negative. 30

The platen 11 carries a stamp 105 which may 35 carry any desirable data, such as numbers to be printed on the back of a print, and this stamp is pivotally attached at 106 to a bracket or carrier 107 which, in turn, is attached to the platen 40 proper by means of adjustable screws 108. A link 109 is attached to the stamp by a pivot 110 and the other end of the link 111 is pivoted to a bell-crank lever 12. Thus, when the platen is moved by the handle 81, the numbering stamp 45 is turned from the position shown in Fig. 7, in which the type 112 contacts with an inking pad 113, to a position in which the legend is printed on a sheet of paper, the type turning until it passes through the opening 114 in the platen. The inking pad 113 may be carried by a bracket 23 attached by screws 116 to the upper table 50 top 6.

The operation of my printing machine may be 55 briefly described as follows: A strip of negatives may be placed in the negative carrier 27 and the rail 36 may be adjusted on the pin 38 and cam 40 or the pin 39 and the cam 41 according to the direction of the exposure frames relative to the film. If the exposures run longitudinally of the film, the pin 38 and cam 40 may be used, if transversely of the film, the pin 39 and cam 41 may be used. In either case, the machine needs only to be set once for each type of film. The negative carrier is then brought into 60 contact with the rail 36 with the first exposure area lying approximately over the light beam passing upwardly through the opening 43 of the masking plate 44. With the platen 11 in a raised position and with the focusing screen 16 in an 65 operative position, in which it will reflect the image of the negative upon the mirror 46, an operator glances in the mirror to see whether the picture frame is correct—that is, to see whether the image will come totally within the opening 70 8, this being shown by the corresponding size of the focusing surface 16. If it does not, the position of the negative holder 36 may be altered by turning the knurled head 42.

A piece of paper may be taken from the paper 75

box 70 and dropped on the printing panel between the guides 71, 71, 73, and 74. This will properly position the paper, and the operator then presses on handle 81 and lowers the platen. This movement removes the movable paper guides 74 from the small apertures 9 and permits the surface 20 to press a sheet of paper P flat over the opening 8. As the handle 81 descends to bring the platen into contact with the paper, the switch 93 is rocked upon its pivot 95, making contact between the wires 98 and 99 and igniting the lamp 48. As the lamp 48 reaches its full brilliance, the shutter 92 rapidly swings out of the light beam and permits an exposure to be made.

As soon as the handle 81 starts to raise, the shutter 93 rapidly cuts off the light and later turns off the lamp. This action occurs with great rapidity.

The operator next positions the next negative for exposure and to do this he depresses the push-button 109 and again watches the image of the frame in mirror 46. Thus, one exposure after another can be rapidly made, and when all of the exposures on a single negative have been made, the carriage 27 is opened and the negative removed.

This machine has been found particularly useful in making enlarged prints from the small negatives used in many of the modern miniature size cameras. Thus, relatively large prints can be rapidly made from small negatives at a cost of labor not exceeding that of ordinary contact prints.

Having thus described my invention, what I claim as new and desire to secure by Letters Patent of the United States is:

1. In a photographic printing machine, the combination with a support, of a printing frame carried thereby, bell crank levers pivoted to the support near the printing panel, one arm of each bell crank lever pivotally supporting a platen, the other arm of each bell crank lever pivotally supporting a focusing plate whereby movement of the bell crank levers upon their pivots simultaneously swing the platen and focusing plate to and from the printing panel.

2. In a photographic printing machine, the combination with a support, of a printing panel carried thereby, bell crank levers pivoted to the support near the printing panel, and extending through said support with one arm of each lever positioned above and the other arm of each lever positioned below said support, one arm of each bell crank lever pivotally supporting a platen, the other arm of each bell crank lever pivotally supporting a focusing plate whereby movement of the bell crank levers upon their pivots simultaneously swing the platen and focusing plate to and from the printing panel and on opposite sides thereof.

3. In a photographic printing machine the combination with a support, of a printing panel carried thereby, bell crank levers pivoted to the support near the printing panel, the bell crank levers having pairs of parallel arms forming sets, a platen pivotally attached to one set of parallel arms, a focusing screen attached to another set of parallel arms whereby the platen and focusing screen may be moved in parallel relation about the pivotal supports of the bell crank levers, simultaneously and in opposite directions with respect to said printing panel.

4. In a photographic printing machine, the combination with a printing panel, of two ele-

ments mounted to move to and from opposite sides thereof including a platen and a focusing plate, means for moving the elements in opposite directions whereby one element may move to the printing panel as the other element moves away from it, said means including four pivotally mounted bell-crank levers all pivotally attached to the base and having their ends all pivotally attached to the elements, the positioning of the pivots being such that each element may be moved on the parallel arms of the bell-crank levers to and from the printing panel, the parallel arms always holding the elements in parallel relation.

5. In a photographic printing machine, the combination with a printing panel, of a platen mounted to move to and from the panel, a focusing plate mounted to move to and from the panel, connections between the platen and focusing plate for moving them at the same time and in opposite directions with respect to the printing panel, a shaft supporting at least a part of the connections between the platen and focusing plate and means for moving the shaft comprising a handle located near and operable in the same direction as the platen.

6. In a photographic printing machine, the combination with a printing panel, of a platen mounted to move to and from the panel, a focusing plate mounted to move to and from the panel, connections between the platen and focusing plate for moving them at the same time and in opposite directions with respect to the printing panel, a shaft supporting at least a part of the connections between the platen and focusing plate and means for moving the shaft comprising a handle located near and operable in the same direction as the platen, and a spring normally holding the platen and handle in a raised position.

7. In a photographic printing machine, the combination with a printing panel including a large printing aperture and a small aperture therein, of a platen mounted to move to and from said printing aperture, a focusing plate mounted to move to and from printing aperture, a stop carried by the focusing plate adapted to move through a small aperture when said focusing plate is moved towards the printing aperture and connections between the platen and focusing plate through which the latter with the stop is moved from the apertures as said platen is moved toward said apertures.

8. In a photographic printing machine, the combination with a printing panel including a large printing aperture and a small aperture therein, of a platen mounted to move to and from said printing apertures, a focusing plate mounted to move to and from printing aperture, a pair of stops carried by the focusing plate and extending through said small apertures for locating printing paper when said focusing plate is near the printing panel, connections between the platen and focusing plate for moving them in opposite directions with respect to said printing panel whereby said stops may be withdrawn from the printing panel before the platen contacts therewith.

9. In a photographic printing machine, the combination with a printing panel including a large printing aperture and a small aperture therein, of a platen mounted to move to and from said printing apertures, a focusing plate mounted to move to and from printing aperture, the platen and focusing plate each being hingedly mounted on opposite sides of the printing panel, connec-

5 tions between the platen and focusing plates for moving them simultaneously in opposite directions with respect to said printing panel, means carried by the focusing plate for locating a sheet of printing paper on the printing panel, said means being adapted to extend through the apertured printing panel.

10 10. In a photographic printing machine, the combination with a printing panel including a printing aperture and small apertures spaced from the printing panel, of a platen moveably mounted and adapted to cover and uncover the printing panel, hooks carried by the platen adapted to pass through the small apertures to engage a sheet of paper positioned on the printing panel and move said sheet with the platen.

15 11. In a photographic printing machine, the combination with a printing panel including a printing aperture and small apertures spaced from the printing panel, of a platen moveably mounted and adapted to cover and uncover the printing panel, spring operated hooks carried by said platen having paper engaging portions projecting below said platen and adapted to extend through said small apertures to engage a sheet of paper carried by the printing panel and hold it substantially parallel therewith.

20 12. In a photographic printing machine, the combination with a printing panel including a printing aperture and small apertures spaced from the printing panel, of a platen moveably mounted and adapted to cover and uncover the printing panel, spring operated hooks carried by said platen having paper engaging portions projecting below said platen and adapted to extend through said small apertures to engage a sheet of paper carried by the printing panel and hold it substantially parallel therewith and means carried by the printer and lying in the path of some of said hooks to release said paper when the platen is moved to an inoperative position.

25 13. In a photographic printing machine, the combination with a printing panel including a printing aperture and small apertures spaced from the printing panel, of a platen moveably mounted and adapted to cover and uncover the printing panel, four pivotally mounted hooks extending downwardly from the corners of the platen, springs tending to move the hooks toward each other, the hooks being positioned to extend through the small apertures of the printing panel when the platen is lowered to an operative position there against, said hooks also being adapted to engage four edges of a sheet of paper laid on the printing panel so as to move it when the platen is moved from its operative position, a pair of releasing arms carried by the machine in position to contact with and release two of the hooks when the platen is moved to an inoperative position spaced from the platen to release the sheet of paper.

30 14. In a photographic printing machine, the combination with a printing panel including a printing aperture and small apertures spaced from the printing panel, of a platen moveably mounted and adapted to cover and uncover the printing panel, four pivotally mounted hooks extending downwardly from the corners of the platen, springs tending to move the hooks toward each other, the hooks being positioned to extend through the small apertures of the printing panel when the platen is lowered to an operative position there against, said hooks also being adapted to engage four edges of a sheet of paper laid on the printing panel so as to move it when the

35 platen is moved from its operative position, a pair of releasing arms carried by the machine in position to contact with and release two of the hooks when the platen is moved to an inoperative position spaced from the platen to release the sheet of paper, and a chute carried by the machine to direct the paper released from the hooks.

40 15. In a photographic printing machine, the combination with a printing panel including a printing aperture and smaller apertures spaced therefrom for receiving a sheet of printing paper, guide plates for locating three sides of the printing paper, a movably mounted guide for the fourth side of the sheet, said movable guide being adapted to project through a small aperture, a platen adapted to cover and uncover the printing aperture, connections between said movable guide and platen for moving the former with the latter but in an opposite direction, and paper engaging hooks carried by the platen and adapted to pass through the small apertures in the printing panel, whereby a sheet of paper located on the panel by the fixed and movable guides may be engaged and removed therefrom by means of the platen moving from its operative printing position.

45 16. In a photographic printing machine, the combination with a printing panel including a printing aperture and smaller apertures spaced therefrom for receiving a sheet of printing paper, guide plates for locating three sides of the printing paper, a movably mounted guide for the fourth side of the sheet, said movable guide being adapted to project through a small aperture, a platen adapted to cover and uncover the printing apertures, connections between said movable guide and platen for moving the guide simultaneously with the movement of the platen whereby the guide may be moved from the aperture as the platen is moved toward the printing panel, means for supporting a sheet of paper beneath the platen, said means including hooks adapted to pass through the same apertures as the movable paper guide.

50 17. In a photographic printing machine, the combination with a printing panel including a printing aperture and smaller apertures spaced therefrom for receiving a sheet of printing paper, guide plates for locating three sides of the printing paper, a movably mounted guide for the fourth side of the sheet, said movable guide being adapted to project through a small aperture, a platen adapted to cover and uncover the printing apertures, connections between said movable guide and platen for moving the guide simultaneously with the movement of the platen whereby the guide may be moved from the aperture as the platen is moved toward the printing panel, means for supporting a sheet of paper beneath the platen, said means including hooks adapted to pass through the same apertures as the movable paper guide, said movable paper guide and paper engaging hooks being mounted to move to and from the platen from opposite sides thereof.

55 18. In a photographic printing machine, the combination with a printing panel including a printing aperture and smaller apertures spaced therefrom for receiving a sheet of printing paper, guide plates for locating three sides of the printing paper, a movably mounted guide for the fourth side of the sheet, said movable guide being adapted to project through a small aperture, a platen adapted to cover and uncover the printing apertures, connections between said movable guide and platen for moving the guide simul- 75

- 5 taneously with the movement of the platen whereby the guide may be moved from the aperture as the platen is moved toward the printing panel, means for supporting a sheet of paper beneath the platen, said means including hooks adapted to pass through the same apertures as the movable paper guide, said movable hooks being adapted to engage and position a sheet of paper before the platen comes to rest as it moves to an operative position upon the printing panel.
- 10 19. In a photographic printing machine, the combination with a printing panel including a printing aperture and smaller apertures spaced therefrom for receiving a sheet of printing paper, 15 guide plates for locating three sides of the printing paper, a movably mounted guide for the

fourth side of the sheet, said fixed and movable guides being adapted to locate a sheet over the printing aperture, a platen adapted to cover and uncover the printing aperture, a plurality of hooks depending from the platen at spaced positions, at least one of the hooks adapted to project through the same aperture as the movable guide, connections between the movable guide and platen for moving the former from the aperture as the latter approaches the aperture, and guiding surfaces 10 on the hooks adapted to pass through the small apertures to reposition a sheet of paper as the platen approaches the printing panel and to cause the hooks to engage the paper when the platen contacts therewith. 15
